UNITED STATES PATENT OFFICE

EDWIN G. NICEWANER, OF JOHNSTOWN, PENNSYLVANIA, ASSIGNOR TO THE LORAIN STEEL COMPANY, OF PENNSYLVANIA.

CAR-BRAKE.

SPECIFICATION forming part of Letters Patent No. 671,117, dated April 2, 1901.

Application filed July 25, 1900. Serial No. 24,736. (No model.)

To all whom it may concern:

Be it known that I, EDWIN G. NICEWANER, of Johnstown, in the county of Cambria and State of Pennsylvania, have invented a new and useful Improvement in Car-Brakes, of which the following is a full, clear, and exact description, reference being had to the accompanying drawings, which form a part of this specification.

10 My invention has relation to car-brakes, and more particularly to that class of car-brakes known as "track-brakes," because of the fact that the brake-shoes are arranged to engage the track-rails in braking instead of 15 the car-wheels.

20 My invention is designed to provide a simple and efficient brake of this type which can be readily applied to different types of car-trucks; and it consists in the novel construction and combination of parts, all as herein-after described, and pointed out in the appended claims, reference being had to the accompanying drawings.

25 In the drawings, Figure 1 is a plan view of a portion of a car-truck equipped with my improved brakes. Fig. 2 is a longitudinal section on the line 2 2, Fig. 1; and Fig. 3 is an end view with the car-wheels partially broken away.

30 The letter A designates the car-wheels, B the axles, and C the side frames, of a truck.

D designates the brake-shoes, which are preferably of considerable length and which may be provided with any suitable or approved braking-surfaces d.

35 E represents suitable castings, which are designed to be bolted, riveted, or otherwise rigidly secured to the truck-frame. In the particular truck shown these castings form the 40 supports for the brake-shoes and their operating devices and are secured to the inner sides of the truck-frames; but it is obvious that the form of the supports may be changed to suit the particular truck in hand and that 45 they may be secured to a cross member or other suitable part of the truck-frame.

F is a rock-shaft which extends transversely across the central portion of the truck and is provided at its ends with bearings f in the castings E. Said shaft at each 50 end portion has a projecting arm F', to whose

free end portion is pivotally connected a short vertical rod G, and to the lower end of this rod are connected two short diverging links H, which are in turn connected to the 55 adjacent ends of the longer arms of oppositely-extending levers K. These levers are respectively fulcrumed in depending arms E' of the castings E, and to their shorter arms are connected short links L, which are in turn 60 connected to the respective end portions of the brake-shoe. Coiled about the rod G is a helical spring M, whose upper end bears against a web or flange e on the casting E and whose lower end seats against a flange or 65 collar g on the rod G.

It will be readily seen that if the shaft F be actuated to raise the arms F' the longer arms of the levers K will also be raised, thereby depressing their shorter arms and forcing 70 the brake-shoes down into engagement with the track-rails. The springs M are compressed by this operation and act to return the shoes to their normal positions as soon as braking pressure is released. I have shown 75 the shaft F as having a lever-arm F'', to which is connected a brake-rod P, which is connected to the usual brake-staff of brake-lever (not shown) on the car-platform.

Since slight modifications within the scope 80 of the mechanic may be readily made in adapting the above-described brake to different types of trucks, I do not wish to limit myself to the exact construction and combination of parts which I have herein shown and described.

Having thus described my invention, what I claim, and desire to secure by Letters Patent, is—

1. In a car-brake, the combination of a 90 brake-shoe adapted for braking engagement with a track-rail, a pair of oppositely-extending levers horizontally pivoted to fixed supports intermediate their ends and connected to the respective end portions of the said shoe, 95 a vertically-reciprocating member attached to the adjacent arms of said levers, and means for actuating the said member.

2. In a car-brake, the combination of a 100 brake-shoe adapted for braking engagement with a track-rail, a pair of oppositely-extending levers horizontally pivoted to fixed sup-

ports intermediate their ends and connected to the respective end portions of said shoe, a vertically-movable rod, loosely connected to the adjacent arms of said levers, and means 5 for actuating the said rod.

3. In a car-brake, the combination of a 25
brake-shoe, adapted for braking engagement with a track-rail, and a pair of oppositely-extending horizontally-pivoted levers having 30
short arms loosely connected to the respective end portions of said shoe, and long arms loosely connected to devices for operating said levers.

4. In a car-brake, the combination of a 35
brake-shoe, adapted for braking engagement with a track-rail, a pair of horizontally-pivoted levers, a vertically-movable actuating-rod, link connections between the said rod and the adjacent arms of said levers, and link 40
connections between the opposite arms of

said levers and the respective end portions of the brake-shoe.

5. In a car-brake, the combination of a 25
brake-shoe, adapted for braking engagement with a track-rail, a pair of horizontally-pivoted levers, link connections between the outer and shorter arms of said levers and the respective end portions of the brake-shoe, a vertically-movable actuating-rod link-connected to the inner and longer arm of each of 30
said levers, a spring acting upon said rod in one direction, and a rocker-arm and actuating means therefor for moving said rod in opposition to the said spring.

In testimony whereof I have affixed my signature in presence of two witnesses.

E. G. NICEWANER.
